PORTRABLE TRACTION UNIT FOR ORTHOPEDIC PATIENTS

Fred Thomas Wright, 1107 Midway Drive, Gastonia, N.C.

Filed Oct. 16, 1961, Ser. No. 67,089

Term of patent 14 years

(Cl. D83—1)

FIGURE 1 is a front elevational view of the portable traction unit for orthopedic patients.

FIGURE 2 is a perspective view thereof; and

FIGURE 3 is another perspective view, but looking in the opposite direction from FIGURE 2.

The rear of the portable traction unit for orthopedic patients is flat and plain.

The dominant features of my design reside in those portions shown in full lines in the drawing.

I claim:

The ornamental design for portable traction unit for orthopedic patients, substantially as shown and described.
